ELECTRIC CLOCK

Filed Sept. 26, 1930

UNITED STATES PATENT OFFICE

JAMES R. PUTNAM, OF WATERBURY, CONNECTICUT, ASSIGNOR TO WATERBURY CLOCK COMPANY, OF WATERBURY, CONNECTICUT, A CORPORATION

ELECTRIC CLOCK

Application filed September 26, 1930. Serial No. 484,477.

My invention relates to an improvement in electric clocks, the object being to simplify and cheapen the construction of the same.

With these ends in view, my invention consists in an electric clock having certain details of construction as will be hereinafter shown and described, the dominant structural feature of my improvement being the elimination of the rear plate commonly used in clock movements.

In the accompanying drawing:

Fig. 1 is a view in front elevation of an electric clock movement constructed in accordance with my invention;

Fig. 2 is a side view thereof with a portion of the motor in section to show the mode of mounting it in my improved motor-support, so as to be unitary therewith;

Fig. 3 is a rear view of the movement;

Fig. 4 is a plan view thereof; and

Fig. 5 is a detached perspective view showing the mode of applying my improved motor-support to the front movement plate.

In carrying out my invention as herein shown, I employ a front movement plate 10 and in lieu of the ordinary complimentary rear movement plate, a one-piece sheet-metal motor-support 11 provided with a pair of corresponding mounting-arms 12 extending forward from it at a right angle to its respective edges and furnished at their forward ends with outwardly-turned perforated fastening-lugs 13 by which they are firmly secured by screws 14 to the back of the plate 10 upon which the motor-support is thus firmly mounted, the motor-support being thus removably secured directly to the front movement-plate.

The motor-support as thus constructed, provides for the sole support of an electric motor having self-contained bearings and interposed between the rear face of the said front plate 10 and the forward face of the said motor-support 11 and small enough in diameter to be installed between the forwardly-projecting mounting-arms 12—12 thereof. To this end the said support is formed with a mounting-opening 15 in which the shouldered rear end 16 of the core 17 of the motor is swaged, whereby the motor is

carried by the support and by it alone. The motor and its support thus form a unit and as a unit are applied to and removed from the movement-plate 10. The motor itself may be of any approved construction, so long as it has self-contained bearings in the sense that its shaft 23 requires no end-bearings external to the motor itself. As shown, it consists of a field-casing 18 having a plurality of pole-fingers 19 and a companion field-casing 20. Upon the said core 17 is wound a coil of high-resistance fine wire 21 interposed between the field-casings 18 and 20 aforesaid. The said casings 18 and 20, the coil 21 and the core 17 form the stator 65 of the motor. Within the core are bushings 22 providing bearings for the motor-shaft 23 and confining a lubricant 24 between them. At its projecting rear end the said shaft 23 is furnished with a starting-button 25 and near its forward end with a rotor 26 mounted on a collar 27 staked upon the said shaft 23 which is furnished at its extreme forward end with a pinion 28 meshing into the first wheel 29 of the movement train. Under this construction the motor is irremovably attached to the said support, with its bearings located within the core of the stator.

The said wheel 29 carries a pinion 30 turning loosely upon a spindle 31, the rear end 80 of which is journalled in and supported by a lug 32 centrally depending from the bridge 11, while its forward end carries the sweep-second-hand 32^a. The said spindle 31 supports and turns within a sleeve 33 carrying 85 the minute-hand 34 and has bearing in a hole 35 in the front plate 10.

The pinion 30 aforesaid meshes into the second wheel 36 of the train and is carried by a pinion 37 turning loosely upon a stud 90 38 riveted in a hole 39 in the front movement plate 10.

The pinion 37 in turn meshes into the third wheel 40 of the clock train which wheel 40 is carried by a pinion 41 staked upon the spindle 31 aforesaid.

The pinion 41 in turn meshes into the fourth wheel 42 of the movement train, the said wheel 42 being carried by a pinion 43 100

turning loosely upon the stud 38 before mentioned.

The pinion 43 meshes into the fifth wheel 44 of the movement train, this wheel being mounted upon the sleeve 33 which mounts a cannon-pinion 45 located in front of the front movement plate 10 and meshing into a minute-wheel 46 turning on a stud 47 riveted in a hole 48 in the front movement plate 10.

10 The pinion 49 of the minute-wheel 46 meshes into an hour-wheel 50 mounted upon an hour-hand socket 51 which turns upon the sleeve 33 aforesaid and carries the hour-hand 52.

15 By providing the motor-support 11 as described for the carriage of the motor and also for furnishing a support and bearing for the rear end of the spindle 31 of the movement train and by further mounting the second 20 and fourth wheels 36 and 42 of the movement-train upon a single stud 38, riveted in the front movement plate, I am enabled to dispense with the rear movement plate commonly used, and so effect a very substantial 25 economy of material and labor in the construction of such clock movements, saving not only sheet-metal stock, but also the several pinion staffs generally employed for mounting the wheels of a movement train, 30 these staffs being commonly journalled at their respective ends in complimentary front and rear movement plates.

I claim:

1. An electric clock-movement having a 35 front movement-plate, a one-piece motor-support removably secured directly thereto, a motor irremovably attached to the said motor-support, forming a unit therewith and having its bearings located within the core 40 of its stator; and a movement-train geared into the rotor of the motor.

2. An electric clock-movement having a front movement-plate, a one-piece motor-support removably secured directly thereto, 45 a motor irremovably attached to the said motor-support, forming a unit therewith and having its bearings located within the core of its stator, a sweep-second spindle journaled at its rear end in said motor-support and also 50 supported by the front movement-plate; and a movement-train connected with the rotor of the motor and in part supported by the said spindle.

55 3. An electric clock-movement having a front movement-plate, a motor-support removably secured directly thereto, a motor irremovably attached to the said motor-support, forming a unit therewith and having its 60 bearings located within the core of its stator, a movement-train driven by the rotor of the motor, and a stud mounted in the said front movement-plate and extending rearwardly therefrom, the second and fourth wheels of 65 the said train being, with their pinions,

sleeved over the said stud by which they are carried and on which they turn.

4. An electric clock-movement having a front movement-plate, a one-piece motor-support removably secured directly thereto, 70 a motor irremovably attached to the said motor-support, forming a unit therewith and having its bearings located within the core of its stator, and a movement-train driven by the rotor of the motor and having running parts supported by the said plate and by the said motor-support.

5. An electric clock-movement having a front movement-plate, a one-piece motor-support removably secured directly thereto, 75 a motor irremovably attached to the said motor-support, forming a unit therewith and having its bearings located within the core of its stator, a sweep-second spindle supported at its rear end in the said motor-support, 80 a stud carried by the said front movement-plate and extending rearwardly therefrom, and a movement-train driven by the running of the motor and including elements mounted 85 upon the said spindle and upon the said stud. 90

In testimony whereof, I have signed this specification.

JAMES R. PUTNAM.
